EVACUATOR

Iris C. Looman, Skellytown, Tex.

Application January 14, 1933. Serial No. 651,788

2 Claims. (Cl. 103—260)

My invention relates generally to means for evacuating wells, such as oil wells, and an important object of my invention is to provide an evacuator which may be operated to cause a thorough intermixture of the several fluid elements in the well before discharging the same from the well.

It is also an important object of my invention to provide an evacuator of the type described which enables heating of the fluid elements in the well so as to liquefy and soften congealable elements and thereby facilitate complete evacuation of the well without incurring stoppage and other faults in the withdrawal of the fluid elements in the well.

It is also an important object of my invention to provide an evacuator of the type described which enables forcing motive fluid into the well so as to evacuate the fluid elements of the well, either by forcing the motive fluid into the casing and between the casing and the flow string, or into the flow string for evacuating the fluid elements of the well through the casing and between the casing and the flow string.

It is also an important object of my invention to provide an evacuator of the type described which may be adjusted in the well casing at different heights above the sand or the like in the well casing so as to exert a suction of varying degrees upon or with respect to the sand, or avoid such an effect upon the sand.

It is also an important object of my invention to provide a process of evacuating a well of the type described, so as to reduce the congealed material in the well to a stage of fluidity and then pass the same out of the well with the discharged fluid elements in the well.

Other objects and advantages of my invention will be apparent from a reading of the following description in connection with the drawings, wherein for purposes of illustration I have shown preferred embodiments of my invention.

In the drawings:—

Figure 1 is a vertical transverse sectional view through an embodiment of the invention in which the motive fluid is forced downwardly through the flow string or pipe.

Figure 2 is an elevational view of another form of the invention.

Figure 3 is a vertical transverse sectional view through an application of the form of the invention shown in Figure 2.

Figure 4 is a horizontal sectional view taken through Figure 1 approximately on the line 4—4 looking in the direction of the arrows.

Figure 5 is a similar sectional view taken through Figure 1 approximately on the line 5—5 looking in the direction of the arrows.

In the drawings, wherein like numerals refer to like parts throughout the same, the letter A refers generally to that embodiment of the invention which is arranged to receive the motive fluid through the flow string or pipe thereof, and the letter B refers generally to that form of the invention in which the motive fluid is forced downwardly between the well casing and the flow string or pipe, and the fluid elements of the well evacuated through the flow string or pipe.

Embodiment A is located at a suitable height in the well casing 5 and comprises a cylindrical body 6 which is of an exterior diameter considerably less than the interior diameter of the well casing 5 so as to be in spaced relation to the sides of the well casing when in use. The body 6 has leading from the upper end thereof and from one side a conduit 7 which is secured in the lower end of a head 8 and in communication with a vertical passage 9 in the head. The head has on its upper end a nipple 10 to which is threaded the lower end of the flow string or pipe 11. Vertical conduits 12 project from the upper end of the body 6 and pass through the head 8 and then into the space which exists above the head 8 between the flow string or pipe 11 and the sides of the well casing 5. Spacing the head 8 from the sides of the well casing and acting as a packing is an annular compressible member 13 which is of dish-shape and is cupped so as to present the concave side upwardly. This is provided to properly position the head 8 in the well casing and to provide a positive stop for any pressure which may be passed downwardly between the flow string or pipe 11 and the interior of the well casing, so as to prevent passage of such pressure below the head. The packer 13 is located at fluid level in the casing.

The cylindrical body 6 has at its lower end an anchor or foot 14 which is of a vertical dimension proper to space the lower end of the body 6 from the sand or other material in the well casing, so as to provide the proper suction with respect to such sand or the like, and avoid direct engagement of the body 6 with such sand or other material. The anchor 14 is relatively reduced and depends from an inverted conical portion 15 in which is located a series of circumferentially spaced vertical passages 16. Each passage 16 has at its upper end an enlarged ball seat in which normally rests a ball check 17. The upper end of each passage 16 communicates with a

relatively enlarged vertical passage 18 in the lower end of which is located a pin 19 for stopping extreme upward movement of the ball check 17. The upper end of each vertical passage 18 5 communicates with an angular passage 20, said passages 20 converging toward the axis of the body 6 where the passages merge as shown at 35. Communicating with the meeting point of the upper ends of the passages 20 is a reduced 10 vertical passage 21 which is located on the axis of the body 6 and is communicated at its lower end with an enlarged generally cylindrical recess 22 which is located in the center of the body 6 between the upper and lower ends of the vertical 15 passages 18. The bottom of the recess 22 is provided with a ball seat in which a large ball check 23 is adapted to seat normally. Communicating with the ball seat and hence with the recess 22 is an opening 24 below the ball seat into 20 which leads a horizontal passage 25 extending inwardly from a vertical passage 26. The passage 26 leads to the upper end of the body 6 where it communicates with the lower end of the pipe 7.

25 Above the meeting point of the angular passages 20 is a conical chamber 27 which is axially located in the body 6 and has a base which is very considerably larger in diameter than the opening communicating it with the upper ends 30 of the angular passages 20. Above the conical chamber 27 is a smaller inverted conical chamber 28 with which the conical chamber 27 communicates by means of the reduced passage or choke 29. Communicating with the inverted 35 conical chamber 28 is a small conical chamber 30 whose upper end is equipped with a ball seat normally receiving a large ball check 31 in a large generally cylindrical chamber 32. The base of the chamber 32 is much larger in diameter 40 than the ball seat for the ball check 31. A cage 33 surrounds the ball seat for the ball check 31 and permits the ball 31 definitely limited freedom in the cylindrical chamber 32. As indicated at 34, the upper end of the cylindrical chamber 32 is somewhat conical but not symmetrical. The lower ends of the pipes 12 leading through the head 8 communicate with the upper end of the chamber 32.

45 The device just described is utilized by placing the same properly in the well casing, then pumping motive fluid down through the flow string or pipe 11. The motive fluid passes through the vertical passage 9 in the head 8 and through the pipe 7 into the vertical passage 26 to the opening 24 so as to raise the ball check 23 and pass through the confining vertical passage 21, whence it passes at high velocity upwardly past the open upper ends of the angular passages 20. This produces a vacuum effect in the angular 50 passages 20 which is communicated through the vertical passages 18 so as to draw the ball checks 17 from their seats and communicate the vacuum to the exterior of the lower end of the body 6, so as to act upon the fluid elements or sand 55 or the like in the well casing, depending upon whether the device is placed close to or is much vertically spaced from the sand or the like. As the fluid elements in the well are drawn upwardly by the said vacuum effect through the passages 16, 18, 20, and meet the motive fluid at the point 35 and enter the conical chamber 27, the various elements are thoroughly mingled together. Then they pass through the choke 29 by which they are further intermingled and 60 mixed. Then they pass into the chambers 28 and 65 30 where they expand, and are thoroughly mixed together, and pass upwardly through the chamber 32 and through the pipes 12 communicated with the chamber 32 to a point above the head 8 and into the well casing between the well 70 casing and the flow string or pipe 11 from where they are withdrawn at the top of the well. It will be observed that the described use of the device of the invention permits the forcing down the flow string or pipe 11 of steam, hot air, hot 75 gas, or other heated fluid, so that the same will intermingle with the fluid elements of the well as they are drawn into the body 6 and passed through the various chambers in the same direction of travel, whereby paraffine may be liquefied and will pass out of the well with the liquid elements without impeding the same or clogging the device. This feature of the invention enables an enormous saving through the elimination of paraffine and other similar troubles, which very greatly cut down the efficiency of well working.

80 Referring to the embodiment shown in Figures 2 and 3, attention is called to the fact that all portions of the device described above are 85 common to the embodiment of the invention B except the upper part of the body which corresponds to the body 6 in Figure 1 in the embodiment A. In the embodiment B the upper chamber 34a, corresponding to the upper chamber 34 in the embodiment A is located somewhat below the upper end of the body 6a and communicates with a rather long vertical passage 36 in a head 37. To the upper end of the head 37 is directly connected the lower end of the flow string or pipe 11a. At one side of the head 37 is a small vertical passage 38 which communicates at its lower end with the small vertical passage 26a which corresponds to passage 26 in the embodiment A. The upper end of the flow string or pipe 11a passes upwardly through one side of a head 8a which is similar in construction and purpose to the head 8 in embodiment A. Above the head 8a a conduit 39 connected to the upper end of passage 38 passes through head 8a and leans 105 slightly inwardly toward the flow string or pipe 11a which passes axially through the head 8a, and opens to the space between the flow string or pipe 11a and the well casing. Like the head 8, the head 8a has the compressible packing member 110 13a which serves a similar purpose and is also to be located at the fluid level in the casing 5.

115 In the employment of the embodiment B, the motive fluid is forced downwardly through the well casing and between the well casing and flow string or pipe 11a and passes into the upper end of the conduit 39 downwardly into the vertical conduit 38 so as to lift the fluid elements of the well in through the various chambers in the body 6a in the same manner as described in connection 120 with the embodiment A. Instead of the evacuated fluid being passed upwardly from the body of the device and to a point between the flow string and the well casing above the packing head, the fluid elements in the embodiment B are 125 passed upwardly through the flow string or pipe 11a. In all other respects the embodiments A and B function similarly and can be employed with equal advantage in appropriate situations.

130 Though I have shown and described herein preferred embodiments of the invention, it is to be definitely understood that I do not desire to limit the application of the invention thereto, and any change or changes may be made in material and structure and arrangement of parts, within the 135 140 145 150

spirit of the invention and the scope of the subjoined claims.

What is claimed is:—

1. In a well evacuator, a body having vertically arranged passages in its lower part opening out through the lower end portions thereof, the upper parts of said passages converging and meeting at their upper ends, said body also having a jet passage vertically arranged therein with its upper end communicating with the meeting upper ends of the first passages, means for introducing fluid into said jet passage, said body having mixing chambers therein, the lower one of which is in communication with the upper ends of the first mentioned passages, and said body having a reduced passage therein connecting the chambers together and a conduit connected with the upper end of the upper chamber.
2. In a well evacuator, a body having a depending reduced portion at its lower end and vertically arranged passages in its lower part opening out through the lower part of the body above the re-

duced portion, said passages having their upper portions converging with their upper ends meeting, said body having a jet passage in its lower part, the upper end of which communicates with the upper ends of the first mentioned passages, a conduit for introducing fluid into the lower end of said jet passage, said body having mixing chambers therein connected together by a small passage, the lower chamber being of substantially conical shape with its large lower end in communication with the upper ends of the first mentioned passages, the other chamber being of double conical shape, the upper end of said body having a cage chamber therein in communication with the upper end of the double cone chamber, a cage in the upper chamber, a valve in the cage for normally closing the upper end of the double conical chamber, a conduit connected with the upper end of the cage chamber, a head through which the conduits pass and a packing carried by the head for engaging a well casing.
